UNITED STATES PATENT OFFICE.

CLINTON H. HUNT, OF STEUBENVILLE, OHIO.

MANIPULATOR FOR FEED TABLES FOR ROLLING MILLS.

1,403,083.

Specification of Letters Patent. Patented Jan. 10, 1922.

Application filed January 6, 1920. Serial No. 349,752.

To all whom it may concern:

Be it known that I, CLINTON H. HUNT, a citizen of the United States, residing at Steubenville, in the county of Jefferson, and 5 State of Ohio, have invented new and useful Improvements in Manipulators for Feed Tables for Rolling Mills, of which the following is a specification.

My invention relates to manipulators for 10 rolling-mill feed-tables.

The object of this invention is to simplify and make more direct and effective the means for turning ingots, blooms, billets, slabs or the like upon feed-tables. This object is secured by providing a mechanism with fewer moving parts and consequently lighter moving masses than are known to me for accomplishing similar results. The power required for overcoming the inertia 20 of motion and rest is correspondingly reduced in my invention. The mechanism of this invention is comparatively simple to manufacture and easy to maintain in operation, and the parts thereof are very easy of 25 access for repairs and replacement. Other objects are referred to hereinafter.

Referring to the accompanying drawings, Fig. 1 is a plan view of one of the many forms which my invention may take, a portion being broken away; Fig. 2, a vertical section on the line II—II on Fig. 1; Fig. 3, a section on the line III—III on Fig. 1; Fig. 4, an elevation of a part of the right hand end of Fig. 1, a portion being in section; Fig. 5, an enlarged plan of a portion of Fig. 1; and Fig. 6, an enlarged detail in vertical section, showing the table-end of one of the rack-bars. Fig. 7 is a view similar to Fig. 3 showing a sliding shoe in place 40 of a roller having travel on the track.

On the drawings, 1 and 2 are parallel metal table girders or frames arranged at opposite sides of the feed table and supporting the ends of the feed-rollers 3 arranged at right angles to the said girders. The rollers are driven by any suitable means, for example, the usual bevel gears 45 driven by the shaft 4.

6 and 7 are parallel metal guides arranged 50 at opposite sides of the feed-table and just above the feed-rollers 3 and at right angles thereto. The inner guide 6 is connected by the bolts 8 to the upstanding portions 9 of three rack-beams 10, the said portions extending up above the top of the feed-rollers

3. The girder 2 has an upwardly-open slot 11 for each rack-beam 10, the table-end thereof resting therein when the beam is fully retracted. This end of each beam has a recess 12, in which a grooved wheel or 60 roller 13 is held by a pin 14, the roller running in an inverted V-shaped track 15 located between and below a pair of consecutive rolls 3. The rollers 13 are covered by 65 housings 16 for the front ends of the beams 10. The intermediate portions of these beams have on their under sides racks 17 which mesh with pinions 21 fixed on the shaft 18, mounted in housings 19 on the bed-plate 20. The remaining ends of the beams 70 10 have the grooved wheels or rollers 22 which run on the inverted V-shaped tracks 23.

Each rack-beam 10 has, in its forward end just back of the housing 16, a vertical slot 75 24 in which is the lever 25 pivoted on the pin 27 carried by the side-members 26 of the beam at opposite sides of the slot 24. Each lever has in front of the pin 27 an arc-shaped slot to receive a reduced portion 6' 80 of the guide 6, this portion occupying the lower rear corner of the guide. See Fig. 2. Each guide 6 is recessed in front at 6^a to receive the auxiliary member 28 of the lever 25, this member being detachable from the 85 remainder of the lever and having its lower end connected to the main member of the lever by a dowel-pin 29 seated in opposed recesses in the two members of the lever. The upper end of the member 28 is secured to 90 the main member of the lever by the removable pin 30. The front side or edge of each member 28 has a nose, lug, or finger 31 lying normally below the top of the rollers 3 and adapted, when the lever is rotated to 95 the right, to travel upwardly in front of the guide 6 and engage an ingot 32 or other article on the rollers and against the guide 6 and rotate it to the left ninety degrees. Each lever has its fulcrum or pin 27 near 100 the top of the table so that the finger 31 will have practically a minimum of travel horizontally and a maximum of vertical travel.

The upper end of each lever 25 has a slot 105 which receives the forward end of a link 33 connected to an upstanding arm 34 on the rock-shaft 35, journalled in bearings 36 on the upper side of the beams 10 near the rear ends of the latter. The shaft 35 may be 110

operated by any suitable power connected to the universal joint 37.

The guide 7 is moved toward and away from the guide 6 by two rack-beams 38 having the portions 40 extending above the rollers 3. To these portions the guide 7 is secured by the bolts 39. The ends of the beams 38 carrying the guide 7 lie in the upwardly open recesses 41 in the girder 1 and 10 between the housings 42 for the ends of the rollers 3. The forward ends of the beams 38 have each a recess for a grooved wheel or roller 43 running on an inverted V-shaped track 44 below and between pairs of consecutive rollers 3 and turning on a pin 45. The intermediate portion of each beam 38 has on its under side a rack 46 meshing with a pinion 47 keyed to the shaft 48 turning in the bearings 49 on the bed-plate 20. The 20 shaft 48 may be operated by any suitable power. The rear ends of the rack-beams 38 have grooved wheels or rollers 50 running on inverted V-shaped tracks 51. The beams 38 travel in upwardly open slots 41" in the 25 girder 6.

The rack-beams 10 and 38 of each pair have on their upper sides a pair of hold-down rollers 52 carried by housings 53 rising from the bed-plate 20. These rollers 30 prevent the beams from rising under the action of the pinions 21 and 47. The rollers are provided with covers 54. The central rackbeam 10 is held down by the roller 55 carried by the housings 56 on the bed-plate. 35 The roller has the cover 57. The two rack-beams 10 and 38 at the lower side are reciprocated by any suitable power, as hydraulic plungers, connected to their rear ends.

By reason of the open top recesses 11 and 40 41', the rack-beams may all be lifted vertically from the table, after the rollers 52 and 55 and their covers have been removed. This results in a large saving of space and a great deal of time. With the manipulators known to me, practically the entire 45 table has to be dismantled in order to allow the guide-operating beams to be removed or to be gotten to for repairs.

Either guide 6 or 7 can be moved over 50 the table by moving one or the other of the rack-beams 10 or 38 at the bottom of Fig. 1, to bring the ingot 32 or other article into the desired position on the table. The guide 7 is frequently brought into use when 55 the ingot or its equivalent is partly turned, it being squeezed between the two guides to complete the edging of a difficult section, such as a wide slab.

In Fig. 7, I show a rack-bar 10 having the 60 shoe 58 sliding on the track 15', the shoe taking the place of the roller 12 and its housing 16. By this construction the bar 10 may be left up between the rollers 3 without the removal of any of the latter.

65 It is one of the particular features of the

construction made possible by my invention that the rack-beams do not extend beyond the table-girder on the working side of the table; that they are placed above the girders and connected directly to the guides; and that the application of power is such as to prevent the bending of the rack-beams. No levers or working parts are under the table or in scale-pits, where they would be subject to undue wear due to scale working into the 75 moving parts. All supporting housings and bases are high relatively to the bottom of the girders, so that no deep pits are required around the table. All parts of the manipulator are accessible for inspection, oiling, 80 repair and replacement.

I claim:

1. In a manipulator for feed-tables for rolling-mills and the like, a feed-table, a guide above the table, a beam secured thereto and reciprocable to cause the guide to travel transversely of the table, a lever carried by bearings on the upper side of the beam and having a portion thereof normally below the feed-table and adapted, when the lever is operated, to travel above the table and beyond the guide, and engage and move an article lying on the table, and means for reciprocating the beam and for operating the lever. 90

2. In a manipulator for feed-tables for rolling-mills and the like, a feed-table, a guide above the table, a beam having one end attached thereto and provided at its table-end with a vertical slot, a lever seated in the slot supported by the beam, and having beneath the level of the table a portion adapted when the lever is operated, to cause the rotation of an article lying on the table, and means for reciprocating the beam and for operating the lever. 100

3. In a manipulator for feed-tables for rolling-mills and the like, a feed-table, a guide above the table, a plurality of beams connected to different points longitudinally of the guide and movable to cause the guide to travel transversely over the table, a lever carried by bearings on the upper side of each beam, each lever having a portion thereof adapted, when operated, to engage and rotate an article on the table, means for reciprocating all the beams simultaneously, and means for operating all the levers simultaneously. 110

4. In a manipulator for feed-tables for rolling-mills and the like, a feed-table, a guide above the table, a plurality of beams connected to different points longitudinally of the guide and movable to cause the guide to travel transversely over the table, a lever carried by the table-end of each beam, each lever having a portion thereof adapted, when operated, to engage and rotate an article on the table, means for reciprocating all the beams simultaneously, and means for 120

125

130

operating all the levers simultaneously, the last named means being supported by the upper side of the beams.

5. In a manipulator for feed-tables for rolling-mills and the like, a feed-table, a guide above the table, said guide being movable transversely of the table and having a vertical slot in its guiding face, a lever pivoted to swing in the plane of the said slot and having an opening in which the guide is located and provided with a removable closure for said opening movable up and down in the slot, and means carried by the said closure and adapted, when the lever is operated, to move upwardly in front of the guide and turn an article lying on the table.
6. In a manipulator for feed-tables for rolling-mills and the like, a feed-table, a guide having a reduced section provided with a vertical slot in the front edge thereof, and a lever having a slot and having an opening in which the guide is located to receive the said section and having a removable closure for said opening movable up and down in the vertical slot, the said member having a portion movable upwardly so as to engage an article on the table.
7. In a manipulator for feed-tables for rolling-mills and the like, a feed-table, a guide above the table, a beam for operating the guide and having a slot at its table-end, and a lever closed around the guide and working in the slot and having means for

engaging and turning an article on the table when the lever is operated. 35

8. In a manipulator for feed-tables for rolling-mills and the like, a feed-table, a guide above the table, a beam for operating the guide and having a slot at its table-end, a lever closed around the guide and working in the slot and having means for engaging and turning an article on the table when the lever is operated, and means for removably securing to the main part of the lever that portion which lies in front of 40 the beam and carries the engaging and turning means.

9. In a manipulator for feed-tables for rolling-mills and the like, a feed-table, a guide above the table, a beam secured thereto and reciprocable to cause the guide to travel transversely of the table, a lever carried by the table-end of the beam and having a portion thereof normally below the feed-table and adapted, when the lever is 45 operated, to travel above the table and beyond the guide, and engage and move an article lying on the table, and means for reciprocating the beam and for operating the lever, the said lever having its bearings at 50 the upper side of the beam and above the table.

Signed at Pittsburgh, Pa., this 3rd day of January 1920.

CLINTON H. HUNT.
